CLAIM

The ornamental design of the bicycle computer with mounting strap, as shown and described.

DESCRIPTION

FIG. 1 is a left side view of the bicycle computer with mounting strap for mounting on a handlebar tube of a bicycle. The right side view would be identical to the left side view.

FIG. 2 is a front view showing the face of the bicycle computer; the indicia thereon is simply for the purpose of illustrating the computer in use and not forming a part of the ornamental design; and

FIG. 3 is a plane view of the mounting strap of the bicycle computer.
